UNITED STATES PATENT OFFICE.

WALTER B. POHLE, OF LYNN, MASSACHUSETTS, ASSIGNOR OF ONE-HALF TO ALFRED CHARLES PAGE, OF WOLLASTON, MASSACHUSETTS.

SPARK-PLUG.

1,391,691.

Specification of Letters Patent. Patented Sept. 27, 1921.

Application filed July 30, 1919. Serial No. 314,318.

To all whom it may concern:

Be it known that I, WALTER B. POHLE, a citizen of the United States, and resident of Lynn, in the county of Essex and State of 5 Massachusetts, have invented new and useful Improvements in Spark-Plugs, of which the following is a specification.

This invention relates to plugs communicating with the interior of the explosion 10 chamber of an explosion motor, and adapted removably to close an opening in the wall of the explosion chamber.

Heretofore, as far as I am aware, spark 15 plugs have been customarily constructed with a central terminal post carrying one of the spark terminals, and insulated from the threaded sleeve by means of which the plug is attached to the engine cylinder, by a bushing of insulating material which is of such 20 character as to afford the proper insulation against the high potential ignition current, and to withstand the high temperature of the combustion chamber of the engine. In order to secure a gas tight joint between 25 the sleeve and the bushing it has been necessary to employ gaskets between the sleeve and the bushing, and screw fittings for retaining the gaskets in place. This construction not only renders the spark plug more 30 expensive to make but renders the plug difficult to disassemble for cleaning. Furthermore, such plugs must be entirely removed from the engine cylinder when it becomes necessary as in cold weather to prime the 35 engine, unless the engine is provided with special priming cocks or other priming equipment.

A principal object of my invention is to overcome the objections hereinbefore noted, 40 to provide a plug which is simple to manufacture, easy to assemble and disassemble for cleaning, and to provide a plug which is so constructed that access may readily be had therethrough to the engine cylinder for 45 the insertion of priming liquid without necessitating the removal of the plug. This object is attained by providing a self-sealing joint between the supporting sleeve and insulating bushing, which automatically 50 seals under the explosion pressure within the engine cylinder, but which may be readily unsealed without removal of the plug sleeve from the cylinder wall for enabling the insertion of priming fluid or to reduce the 55 compression within the engine cylinder to

enable the engine to be more easily cranked, or unsealed after the removal of the plug for adequately cleaning the terminals of the plug.

I will now describe the invention in connection with one illustrative species of the genus of my invention. 60

In the accompanying drawings—

Figure 1 is an elevational view of my improved spark plug; 65

Fig. 2 is an end view of the plug showing the construction and arrangement of spark terminals;

Fig. 3 is an elevational view of my improved plug the supporting screw-threaded 70 sleeve being shown in section to better disclose the self-sealing joint between the sleeve and the insulating terminal post bushing;

Fig. 4 is a view similar to Fig. 3, but showing the terminal post depressed within the 75 sleeve to enable the insertion of priming fluid;

Fig. 5 is a longitudinal axial section taken on the line 5—5 of Fig. 1;

Fig. 6 is a detail view showing a modified 80 form of spark plug; and

Fig. 7 is a top view of the plug shown in Fig. 6.

In the drawings I have illustrated my improved spark plug as comprising a threaded 85 sleeve 1 having a hexagonal nut portion 2 and provided with a tapered bore 3. The taper of the bore is made very gradual, the greatest diameter of the bore being at the threaded end of the sleeve. Positioned 90 around the threaded end of the sleeve 1 and extending therefrom parallel to the axis of the sleeve are spark terminals 4. Slidable within the sleeve 1 is a terminal post 5 provided at its lower end with a collar 6 and a 95 perforated disk 7 which serves as a spark terminal and which coöperates with the terminals 4.

The post 5 is surrounded by a tube 8 of 100 insulating material upon which are assembled a plurality of washers 9 of suitable heat-resisting insulating material such as pressed cotton-fiber or mica. These washers are clamped together to form a compact bushing member by means of a washer 10 105 and a nut 11 which has threaded engagement as at 12 with the upper end of the terminal post 5. The bushing is tapered from the lower end thereof toward the upper end thereof to correspond to the taper 11

of the bore of the sleeve 1 so that when the bushing is positioned within the sleeve as shown in Fig. 3, a gas-tight joint is formed between the sleeve and the bushing. A 5 knurled thumb-nut 13 is threaded upon the upper end of the terminal post 5 by means of which an ignition cable may be connected to the terminal post. The knurled portion of this nut is made of slightly greater diam- 10 eter than the diameter of the upper portion of the bore 3 of sleeve 1 so as to prevent the insulated terminal post 5 from dropping into the engine cylinder when the post has been depressed within the sleeve as shown 15 in Fig. 4 for the insertion of priming fluid.

In Figs. 6 and 7 I have shown the knurled thumb-nut 13 provided with a notch 14 which communicates with the circumferential channel 15 of the nut. This notch in 20 coöperation with the channel 15 serves to conduct fluid from the spout of a suitable priming vessel as for example an oiling can, to the annular space formed between the sleeve and the insulating bushing of the 25 terminal post when the post has been depressed to such a position that the lower face of the knurled portion of the nut 13 rests upon the upper face of the sleeve 1.

Under normal operation conditions the 30 respective parts of the plug occupy positions such as shown in Fig. 1 and the tapered insulating bushing of the terminal post 5 is forced into a gas-tight relation with the tapered bore of the sleeve 1, by the force of 35 the explosions within the firing chamber of the engine, which force is applied against the bottom of the bushing and against the spark terminal disk 7. The contact between the bushing and sleeve is very intimate 40 owing to the length of the contact surface and the wedging action of the tapered bushing against the tapered wall of the bore 3. When it is desired to prime the engine cylinder it is only necessary to depress the 45 terminal post with the bushing thereby separating the bushing from the sleeve thus providing an annular space therebetween through which the priming fluid may be injected into the firing chamber. When 50 the terminal post is depressed the compression within the firing chamber is released and the engine may then be more easily cranked. Upon the first explosion, however, 55 the plug automatically seals the firing chamber and thereafter functions in the usual manner.

The construction hereinbefore described renders the spark plug readily disassembled for cleaning. To clean the plug the sleeve 1 is first unscrewed from the cylinder. The

knurled nut 13 is then removed and the entire terminal post removed from the sleeve. Access may then be had to the spark terminals 4 on the sleeve and to the disk terminal 7 on the post, so that they may be 65 thoroughly cleaned. This is not possible with the ordinary spark plug.

While I have illustrated a disk terminal 7 for coöperation with the spark terminals 4, it is apparent that the terminal 7 might 70 be of any other suitable shape.

From the foregoing description it is apparent that I have provided an improved spark-plug which requires no gaskets, which is self-sealing, which is easily disassembled 75 to expose the entire surface of the spark terminals for proper cleaning, which is so constructed that priming fluid may be injected into the firing chamber through the spark-plug sleeve without removing the 80 plug, and which is simple in construction and relatively inexpensive to manufacture.

I claim:

1. In a spark plug the combination of a sleeve having a tapered bore, a spark terminal thereon, a terminal post slideable within said sleeve and insulated therefrom by an insulating bushing tapered to form a gas-tight joint with said sleeve in the raised position of said post within said sleeve, a 90 spark terminal carried by said post, and a binding post nut having screw-threaded engagement with the upper end of said post, said nut having an external diameter greater than the diameter of the bore of 95 said sleeve, whereby when said post is depressed within said sleeve, said post is prevented from passing entirely through said sleeve.

2. In a spark plug the combination of a 100 sleeve having a tapered bore, a spark terminal thereon, a terminal post slideable within said sleeve and insulated therefrom by an insulating bushing tapered to form a gas-tight joint with said sleeve, a spark terminal 105 carried by said post and a binding post nut having a screw threaded engagement with the upper end of said post, said nut having an external diameter greater than the diameter of the bore of said sleeve and provided 110 with a notch in the circumferential surface thereof which when said post is depressed within said sleeve communicates with the annular space between the surfaces of said bore and post whereby priming fluid may 115 be injected.

Signed by me at Boston, Massachusetts, this twenty-first day of July, 1919.

WALTER B. POHLE.
